UNITED STATES PATENT OFFICE.

EDWARD DANNER, OF TOLEDO, OHIO, ASSIGNOR TO THE LIBBEY GLASS COMPANY,
OF TOLEDO, OHIO, A CORPORATION OF OHIO.

BAR AND TUBING SEVERING MEANS.

Application filed August 7, 1922. Serial No. 580,037.

This invention relates to bar or tube severing means for use more particularly in connection with apparatus for continuously forming molten material, such, for instance, as glass, into cane or tubing and adapted to sever the cane or tubing into predetermined lengths at a distance from the forming apparatus.

In my former United States Letters Patent No. 1,220,201, dated March 27, 1917, I show a severing mechanism having a reciprocatory form of cutter which moves lengthwise of the material being severed or scored while acting thereon and then returns to engage the material so that the material is scored or weakened at predetermined points lengthwise thereof as it passes along. This machine is satisfactory in its operation when operating on material not moving at too rapid a speed. It is found, however, that if the speed of movement of the material is much over 200 feet a minute, the severing or scoring means must reciprocate so rapidly as to cause vibration, thereby rendering its use objectionable.

The object of the present invention is the provision of a simple, durable and efficient severing or scoring means of the class described which is adapted to operate on material feeding or moving at a very high speed without causing objectionable jar or vibration.

A further object of the invention is the provision of simple, efficient and novel means for effecting a lateral bending or deflection of the material acted on after a scoring operation to effect a breaking off of the material at the scored or weakened point.

Further objects and advantages of the invention will be apparent from the following detailed description thereof.

While the invention in its broader aspect is capable of embodiment in numerous forms, a preferred embodiment thereof is illustrated in the accompanying drawings, in which,

Fig. 1 is a top plan view of a machine embodying the invention with a part broken away. Fig. 2 is a cross-section thereof on the line 2—2 in Fig. 1. Fig. 3 is a side elevation thereof with a part broken away. Fig. 4 is an enlarged top plan view of the scoring unit with the driving motor broken away and with a part in central longitudinal

section. Fig. 5 is a front end elevation of the machine with the scoring unit in scoring position. Fig. 6 is an enlarged section taken on substantially the line 6—6 in Fig. 5, with parts in full. Fig. 7 is an outer end elevation of the scoring head showing by dotted lines its position when first moved into scoring contact with the material. Fig. 8 is an enlarged elevation of the cam means for controlling the vertical rocking movements of the scoring unit. Fig. 9 is a central vertical section of the material breaking off unit taken on the line 9—9 in Fig. 1 with parts in full. Fig. 10 is a vertical section thereof taken on the line 10—10 in Fig. 1, and Fig. 11 is an outer side elevation of said unit slightly modified to provide a different form of deflecting or breaking off means for the material.

Referring to the drawings, 1 designates the frame of the apparatus, which frame is preferably in the form of a platform. Two bearings standards 2 and 3 rise in spaced relation from the frame at a side thereof, the rear standard having a pair of stub shafts 4 projecting therefrom in vertically spaced relation and carrying upper and lower sprocket wheels 5, and the forward standard having upper and lower bearing shafts journaled therein and carrying vertically spaced sprocket wheels 8. The sprocket wheels 5 and 8 of each set are connected by feed chains 9, the upper flight of one cooperating with the lower flight of the other to grip and impart a forward feeding movement to the work bar or tube *a* passing therebetween.

Each shaft 6 and 7 extends crosswise of the frame 1 and is journaled at one end in a bearing 10 and each carries a gear 11 at such end, which gears are of like size and in mesh to cause a driving of one shaft from the other. A gear 12 on the shaft 7 is in mesh with and driven by a gear 13 on a shaft journaled in suitable bearings at a side of the shaft 7 and carrying a large gear 14, 100 which is in mesh with and driven by a pinion 15 on the shaft of a motor 16 that is mounted on the platform 1. No novelty is claimed for this work feeding means as it is substantially the same as shown and described in my said former patent. It will be understood that the work bar or tube *a* passes from its forming source to and be-

tween the feed chains 9 and the speed of drawing of the work depends on the speed of the drawing or feeding chains.

The work after leaving the feed chains 5 passes through a guide 17 thence between a pair of horizontally spaced guide rolls 18 over a yielding table or supporting member 19, and thence through a forward guide 20 into position to be engaged by the breaking 10 off unit which is mounted at the forward end of the platform.

The work scoring or weakening means, which is intended to act at predetermined spaced points on the work, and in which one 15 of the features of the present invention resides, will now be described. A shaft 21 is journaled lengthwise of the frame 1 in standards 22 rising therefrom and is in driven connection at its rear end with one 20 of the shafts 6, 7, the latter in the present instance, through a pair of gears 23, a shaft 23^a and a set of bevel gears 23^b. A table 24 is loosely mounted on the forward end portion of the shaft 21 over or in straddling 25 relation to the forward bearing 22 to permit a vertical rocking of the table relative to the shaft 21 and platform 1. A shaft 25 is journaled in the under side of the table 24 substantially longitudinally of the table 20 and projects from adjacent to the shaft 21 to which it is connected by a set of bevel 30 gears 26 toward the adjacent side of the work *a*. A cam wheel 27 is fixedly mounted on the shaft 25 and is engaged at its under 35 side by a supporting roll 28, which is carried by the upper forked end of a stem 29 that is mounted for vertical adjustment in a bearing bracket 30 projecting from a side of the forward bearing standard 22. The 40 stem 29 is threaded in a nut which is rotatably carried by the bracket 30 and this nut is in beveled gear connection with a control shaft 31 to which a crank or wrench may be fitted to effect a turning of the same when 45 it is desired to vertically adjust the stem. It is evident that the engagement of the roll 28 with the cam 27 supports the table 24 in proper position and that at each rotation of the cam 27 predetermined raising and lowering 50 movements are imparted to the cam 27, which in turn imparts a corresponding rocking movement to the table 24. The weight of the table and parts carried thereby retains the cam wheel in engagement with 55 the supporting roll.

A motor 32 is mounted on the rear end portion of the table 24 and has its motor shaft 33 mounted in and projecting through a bearing 34 rising from what may be 60 termed the forward end of the table or the end thereof adjacent to the work *a*. The shaft 33 is preferably provided with a flexible joint 35 between the motor and bearing. A bushing 36 (Fig. 4) is mounted on 65 the shaft 33 and extends into the bearing

34, and a hub sleeve 37 is mounted on the forward end of this bushing and has collars 38 and 39 thereon, the former being disposed at the forward end of the bushing and being removable to permit a removal of the 70 hub sleeve from the bushing. The hub sleeve 36 at its forward end carries a circular head 40 forming a gear case 41 therein and has an entrance opening which is closed by a removable plate 42. 75

The gear case 41, in the present instance, is of L-form and encloses a train of gears which connects the shaft 33 with a cross-shaft 43 journaled centrally in the circular head 40 and carrying a scoring disc or wheel 80 44 within the head. An edge of the wheel 44 projects slightly from an edge of the head through an opening therein, which is disposed at one side of the axis of the shaft 33. The gear train, in the present instance, comprises a pair of mitre gears 45, which connect the shaft 33 with a pinion 46, which in turn drives a pinion 47 in mesh with a pinion 48 fixed to the shaft 43. The pinion 46 and 47 are mounted on suitable shafts 90 provided in the gear case 41 in parallel relation to the shaft 43. The axis of the scoring wheel 44 intercepts the axis of the shaft 33 in advance thereof, and the scoring wheel is disposed centrally of the sides of the head 95 40 and in a plane common to an axial plane of the shaft 33, as best shown in Fig. 4. The side of the head 40 opposed to the gear case 41 is provided with a removable part 49 to facilitate access to the scoring wheel 44 100 and the removal or replacement thereof. The pressure of the scoring wheel 44 on the work may be varied by any suitable counterbalancing weight, not shown, longitudinally of the motor carrying end of the frame 24, such weight being carried by the 105 frame for this purpose. In practice the scoring wheel bears against the work at a pressure of four or five pounds. This pressure, however, may be varied as desired. 110

In order that the head 40 may be balanced with respect to its turning axis, the removable part 49 thereof is provided with chambers 50 for receiving a liquid or solid in sufficient quantity to counterbalance the 115 weight of the gearing and gear casing. The wheel 44 is provided with a hardened and removable circular blade portion which projects at its edge beyond the body portion of the wheel and through the edge opening in 120 the head 40 for scoring coaction with the work.

The shaft 25 carried by the table 24 is in permanent driving connection with the hub sleeve 37 of the head 40 through a pair 125 of gears 51. It is thus evident that a rotation of the shaft 25 in addition to imparting predetermined rocking movements to the table 24 and parts carried thereby, through the medium of the cam wheel 27 and sup- 130

porting roll 28, also imparts rotation to the head 40 and scoring wheel 44 about the axis of the shaft 33 and in a plane parallel to the axis of rotation of the shaft 43 carrying the wheel. At the same time the driving action of the motor 32 imparts a rapid rotation to the shaft 33 and through the interposed train of gears to the scoring wheel. The turning of the head is so timed 10 with respect to the vertical rocking movements of the table and head that the exposed work coating edge of the scoring wheel will traverse a lower arc a, b (Fig. 7) of its movement during the last portion of 15 each lowering movement of the head with the table 24.

The head 40 is disposed over the portion of the tube or cane a between the guides 17 and 20, and the normal line of travel of the 20 work a is in intercepting relation to the scoring edge of the wheel 44 when in its lowered position so that the wheel in lowering and turning into contact with the work will cause a lowering of the work and will 25 have scoring coaction therewith throughout a predetermined portion of the arc a, b as illustrated in Fig. 7. The scoring wheel is driven at a high speed so that an effective scoring or weakening of the work at the 30 point of contact of the wheel therewith will take place during the period of contact of the wheel and work. It is evident that the turning speed of the head should correspond to the speed of feeding of the work a so that 35 no slippage of the work lengthwise of the latter will occur during a scoring action. It is also evident that the vertical rocking of the table 24 and parts carried thereby may be so timed that the scoring wheel will 40 have scoring coaction with the work at each rotation of the head 40 or once for each of a desired number of rotations of the head depending on the length of the sections into 45 which it is desired to sever the work.

The work a is yieldingly supported below the point of contact therewith of the scoring wheel by the table 19 which is pivoted at one end to a support 55 (Fig. 3) for limited 50 vertical rocking movements and has its free end portion yieldingly supported by an adjustable yieldable support 56, which is carried by the standard 55.

The breaking off means for the work a after each scoring operation, is carried by a 55 frame part 1^a at the forward end of the platform 1 and has a set of opposed peripherally recessed engaging wheels 57 between which the work passes after leaving the guide 20 and which are vertically movable together 60 at predetermined intervals relative to the guide 20 to impart a lateral breaking off movement to the work. The wheels 57 are carried by respective upper and lower shafts 58 and 59, the former being mounted in a 65 bearing block 60 and the latter in a bearing

block 61. These bearing blocks are mounted for vertical reciprocating movements in vertical guideways 62 provided in opposite sides of the frame 1^a and are yieldingly spaced apart by interposed coiled compression springs 63, which act at one end against adjusting screws 64 carried by the upper bearing block 60. The lower bearing block 61 is yieldingly supported by coiled compression springs 65 near opposite ends thereof and having their lower ends thrusts against members 66, which are threaded for vertical adjustment in laterally projecting portions of a base member 67 of the frame 1^a. The springs 65 encircle guide stems 68 70 projecting down from the bearing block 61. It is thus evident that the blocks are yieldingly spaced by the springs 63 and are yieldingly supported by the springs 65, the latter being weaker than the springs 63. The slide 75 block 61 has shoulders 69 at opposite sides thereof adapted to have stop coaction with stop members 69^a on the frame 1^a to limit the upward movement of the slide block.

A drive shaft 70 for the operating parts 90 of the breaking off mechanism is journaled in the frame base 67 and extends lengthwise of the frame 1 along one side of the interior portion thereof and is connected by a set of bevel gears 71 (Figs. 2 and 3) to a counter-shaft 72 which is journaled in suitable bearings crosswise of the frame 1 and is in driven connection with the shaft 7 through a set of spur gears 73. If it is desired to change the speed of driving of the shaft 72 from 100 the shaft 7 the gears 73 are disconnected and another set of gears 74 of different size are placed in mesh. A shaft 75 is vertically journaled in the frame 1^a and its base 67 and is driven from the shaft 70 105 through a set of bevel gears 76 disposed within the frame base 67 (Fig. 9). The shaft 75 has two spiral gears 77 splined thereon for axial movements on the shaft and one is disposed within a bearing portion 110 78 provided in the vertically movable block 60 and the other is mounted within a bearing portion 79 in the block 61. The upper gear 77 is in driving mesh with a spiral gear 80 on the shaft 58 and the lower gear is in 115 driving mesh with a gear 81 on the shaft 59 so that a driving of the shaft 75 imparts rotation in unison to the shafts 58 and 59 and the feed wheels 57 carried thereby, the gearing being such that the shafts are driven in 120 opposite directions.

A cam wheel 85 is mounted on the forward end of the shaft 70 in advance of the frame base 67 and peripherally coacts at its bottom portion with a roll 86, which is 125 rotatably carried by the outwardly turned foot portion of a slide 87, which has a vertical slot 88 receiving the shaft 70 and is guided for vertical reciprocating movements by the front portion of the base frame 67. 130

A stem 89 is attached to the upper end of the plate 87 and extends upward therefrom through a vertically registering portion 90 of the bearing block 60, being threaded in said portion for vertical adjustment relative thereto. The adjustment of the plate 87 and stem 89 with respect to the bearing block 60 and cam 85 is such that the roller 86 is at all times held against the face of the cam 10 wheel, and the form of the cam is such that at each revolution thereof a predetermined lowering movement is imparted to the plate 87 and through it to the bearing block 60. The bearing blocks 60 and 61 being yieldingly spaced by the spring 63 and mounted for vertical floating movements together against the tension of the spring 65, the two blocks are caused to have vertical reciprocatory movements in unison and such movement is communicated to the work engaging wheels 57. The gears 77 during such movements slide longitudinally of the shaft 75. When the wheels 57 are in elevated position the space therebetween is in the 25 normal line of feed of the work α and a lowering of the wheels imparts a downward deflecting or bending movement to the work and effects a breaking off of the same at a point thereon which is scored or weakened 30 by the action of the scoring wheel 44.

Upon a raising of the bearing blocks 60 and 61 to their upper or normal positions, the movement of the block 61 is stopped before that of the block 60 by reason of the 35 parts 69 striking the stops 69^a, the springs 63 then acting to cause a slight continued upward movement of the upper block to effect a spacing of the feed wheels 57 to release the work. The lowering movement of 40 the blocks 60 and 61 and the consequent drawing together of the feed wheels 57 to have gripping or feeding engagement with the work is timed to take place during a 45 scoring operation, the breaking-off action of a work section taking place approximately when the scored point on the work is substantially over the rigid or pivoted end portion of the supporting table 19 so that such end portion of the table acts as a fulcrum for 50 the work during the breaking-off operations.

It is found in practice that by imparting a lateral deflecting or breaking-off strain to a work piece in advance of a scored point, the material usually has a ragged or irregular break, which is objectionable. I have discovered that by exerting a pull on the work piece simultaneously with the lateral deflecting or breaking-off strain thereon, a clean break of the work is effected at the 55 scored point. This is accomplished by making the peripheral speed on the rolls 57 slightly greater than the speed of movement of the work so that a slight slipping of the wheels on the work and a consequent longitudinal pulling of the work will be effected. 60 65

A modification of the work breaking-off means is shown in Fig. 11 wherein the slide plate 87 and the roll 86 are lowered from operative coaction with the cam wheel 85, the work engaging wheels 57 are removed 70 from the shafts 58 and 59 and a cam wheel 91 is mounted on the shaft 58 and is adapted to have peripheral wiping and downward deflecting engagement with the work α in advance of the guide 20 at each revolution 75 of the cam. In this form the bearing block 60 stands at all times in raised position and its upward movement is limited by a block 92 inserted between it and the upper end 80 wall of the guideway 62. The use of this form of breaking-off means is preferable when the work is being run at a very rapid speed, say, from 300 to 1000 feet a minute, but when running the work at a less speed, the form of breaking-off means shown in 85 Figs. 9 and 10 is preferred.

The operation of my machine is as follows:

It will be understood that the work bar or tube advanced from a furnace or other 90 source of supply between the feed chains 9 by which it is drawn forward from the source of supply and advanced through the guides 17 and 20 beneath the scoring head 40 and thence between the opposed breaking-off wheels 57, or beneath the breaking-off cam 91, as the case may be, at a uniform predetermined speed. The scoring wheel 44 is driven at very high speed by the motor 32 and at the same time is rotated about the 100 axis of the motor shaft 33 from the shaft 21 through the intermediate driving connection 25, 26 and 51, and also has vertical rocking movements imparted thereto from a rotation of the shaft 25 carried by the 105 table 24 by the coaction of the cam 27 with the supporting roll 28. The rocking of the table 24 causes the scoring wheel 44 to lower into scoring engagement with the work at predetermined intervals so that the scoring occurs at uniformly spaced points on the work. The rotation of the scoring wheel about the axis of the shaft 33 is so timed with respect to the rocking movements of the table 24 and parts carried thereby that the exposed edge of the scoring wheel will have contact with the work for a short period at each lowering movement of the wheel, the work being pressed down against the opposed tension of the supporting table 110 18 during the scoring action of the wheel therewith. The turning speed of the exposed edge of the scoring wheel about the axis of the shaft 33 corresponds to the speed of advancing movement of the work so that the wheel will only have contact with the work at one point thereon during a predetermined arc of rotation of the wheel about the axis of the shaft 33. The use of the scoring wheel on the work causes a shallow 115 120 125 130

notch to be cut in the surface thereof at a point where it is desired to have the work subsequently broken and the frictional co-action of the scoring wheel with the work 5 in addition to cutting or notching the same also effects a localized heating thereof at the point of contact so that an abnormal strain is set up in the glass and renders it more brittle at such point to facilitate 10 breaking off. When a predetermined length of work has advanced between the breaking off rolls 57 the cam wheel 85 causes a depression of the vertically floating blocks 60 and 61 through the intermediate connecting 15 means 86, 87 and 89 and a corresponding movement to the wheels 57 to cause a gripping of the work thereby and a quick downward deflecting or bending of the work and a consequent breaking-off or severing of the 20 same at the adjacent scored or weakened point. The wheels 57, due to their greater speed, cause a pulling stress to be applied to the work to assist in breaking off the same. The cam-wheel 85 then permits the floating blocks 25 to raise into normal positions under the action of the springs 65.

It is evident that with my new scoring means the work may be fed through the machine at a very rapid speed, for instance, 30 four or five hundred feet per minute, without the movement of the scoring mechanism imparting any noticeable vibration or rocking action to the machine.

I wish it understood that my invention is 35 not limited to any specific construction, arrangement or form of the parts, as it is capable of numerous modifications and changes without departing from the invention.

40 Having thus described my invention, what I claim as new, and desire to secure by Letters Patent, is,—

1. In a machine of the class described, a 45 rotatable work scoring wheel, a mounting for the wheel rotatable about an axis intersecting the wheel diametrically, and means for rotating the wheel and its mounting simultaneously.

2. In a machine of the class described, a 50 driven shaft, a work scoring wheel carried by the shaft, a carrier for the shaft rotatable about an axis intersecting the wheel diametrically, and means for rotating the shaft and its carrier simultaneously.

55 3. In a machine of the class described, a rotatable housing, a work scoring or cutting wheel journaled in the housing with a working edge projecting from the housing at one side of the housing axis, and with 60 said axis intersecting the wheel diametrically, and means for driving the member and housing simultaneously and continuously.

4. In a machine of the class described, a 65 rotatable housing, means for rotating the housing, a work scoring or cutting wheel

journaled in the housing with its working edge projecting from the housing at one side of the housing axis and with said axis intersecting the wheel diametrically, and means for driving the member and housing 70 simultaneously and continuously.

5. In a machine of the class described, a work scoring or cutting member adapted to score elongated work transversely, and means for imparting predetermined reciprocal movements to the member transversely of the work operated on and means connected to operate in timed relation with the first said means and adapted to impart predetermined rotation to the member in a 75 plane lengthwise of the work acted on.

6. In a machine of the class described, a scoring or cutting member mounted for rotation about different axes, separate means for simultaneously and continuously rotating the member about different axes, and means, connected for operation in timed relation to one of said rotating means, for moving the member into and out of work 85 engaging position transverse to the work 90 being acted on.

7. In a machine of the class described, a scoring or cutting wheel, means carrying the wheel for rotation about axes intersecting each other at the center of the wheel, and means for imparting continuous rotation to the wheel about each of said axes. 95

8. In a machine of the class described, a scoring or cutting wheel, means carrying said wheel for rotation about axes intersecting each other at the center of the wheel, and separate means operable to rotate said wheel about each of said axes. 100

9. In a machine of the class described, means mounted for rocking movements and including a scoring or cutting member rockable with the means and carried thereby for rotary movements in different planes, means for imparting predetermined successive rocking movements to the first means, and means 105 for continuously rotating the rotatable member of the first means in one of its different planes of rotation in timed relation with said rocking movements. 110

10. In a machine of the class described, 115 a frame mounted for rocking movements, a scoring or cutting member carried by the frame for rotary scoring or cutting movements about one axis, and for rotating about a different axis to successively turn a working edge of the member into work-engaging position, means for imparting separate rotation to the member about different axes, and means for rocking the frame to move the member into and out of work cutting position in timed relation to its rotation about 120 said different axis. 125

11. In a machine of the class described, a frame mounted for rocking movements, a shaft journaled in the frame, means for driv- 130

- ing said shaft, a head mounted for turning movements about the shaft axis, a work scoring or cutting member journaled in the head with its axis at an angle to the shaft axis, 5 means connecting the shaft and member for rotating the member about its axis from a rotation of the shaft, means for rotating the head about the shaft axis, and means for rocking the frame in predetermined relation 10 to the speed of rotation of the head.
12. In a machine of the class described, a shaft, a mounting for the shaft, a housing mounted for free rotation on the shaft, means for driving the shaft, means for imparting rotation to the housing, a scoring or cutting wheel mounted in the housing with its cutting edge in the plane of the shaft axis, said wheel having an edge portion projecting without a portion of the 15 housing, and driving connection between the shaft and wheel.
13. In a machine of the class described, a housing mounted for rocking movements in one plane and for rotary movements in a 20 different plane, a rotatable scoring member mounted within the housing and having a working edge portion projecting therefrom, the axis of rotation of the member being at an angle to the axis of rotation of the housing, means for rotating the scoring member, 25 and means operable to impart both rocking and rotary movements to the housing.
14. In a machine of the class described, means for continuously feeding an elongated 30 work piece longitudinally through the machine, a scoring wheel rotatable to move its edge transversely of the work, a mounting for the wheel, means to rotate the mounting to move the work-contacting edge of the 35 wheel in the longitudinal direction of the work, and means adapted to rock the mounting transversely of the work to cause intermittent contact of the wheel with the work.
15. In a machine of the class described, 40 means for feeding a work piece continuously from a source of supply, a work scoring or cutting member mounted for rotation in different planes and for reciprocatory movements to and from work-engaging position, and mechanism for rotating the member 45 about its different axes of rotation and imparting reciprocatory movements thereto whereby the member is rocked into and out of engagement with the work, is rotated in the direction of movement of the work and at uniform speed therewith and is rotated to score or cut the work when in engagement therewith.
16. In a machine of the class described, 50 means for continuously feeding a work piece from a source of supply, and mechanism automatically operable to periodically act on the work piece to score or cut the same at predetermined spaced intervals, said mechanism comprising a head mounted for re- 55 ciprocatory movements toward and from the work and for rotation in the longitudinal plane of movement of the work, cutting or scoring members carried by the head for rotation transverse to the work, means for 60 imparting scoring or cutting rotation to the member, and means for rotating and imparting rocking movements to the head into and out of engagement with the work, the rotation and rocking of the head being in 65 timed relation with each other and with the speed of movement of the work.
17. In a machine of the class described, means for continuously feeding a work piece from a source of supply, mechanism 70 automatically operable to periodically act on the work piece to score the same at predetermined spaced intervals lengthwise thereof and continuously rotatable means 75 acting on the work in advance of the scoring means and periodically operable to effect a lateral deflection of the work to break it in two at a scored point.
18. In a machine of the class described, means for successively scoring a work piece 80 longitudinally thereof as it feeds from a source of supply, and mechanism operable to act on the work in advance of the scoring mechanism to periodically effect a lateral deflection of the work from its course of 85 movement to break the same in two at a weakened point, said mechanism including a continuously rotatable member for coaction with the work.
19. In a machine of the class described, 90 means for acting on a work piece of elongated brittle material to successively score the same at predetermined spaced points longitudinally thereof, a rotary member engaging the work piece in advance of the 95 scoring means, means driving the member at the speed of movement of the work piece, and means carrying the wheel and operable to periodically move it transverse to its axis 100 to effect a breaking-off deflection of the work piece from its normal line of feed.
20. In a machine of the class described, mechanism for acting on a work piece of elongated form to successively deflect the 105 work piece from its normal line of feed to break a section from the forward end thereof, said mechanism comprising a vertically movable shaft, a work piece engaging wheel on the shaft, power means for driving the shaft and wheel, and means normally retaining the shaft in one position of its movement and operable to transversely move the same to cause its wheel to exert a lateral 110 breaking-off pressure on the work piece.
21. In a machine of the class described, a 115 wheel beneath, at one side of and in engagement with a longitudinally feeding work piece, means carrying the wheel for movements transverse to the work piece, power 120 means for driving the wheel and means for 125

- periodically imparting transverse movements to the wheel to cause it to exert a lateral breaking off strain on an engaged work piece.
- 5 22. In a machine of the class described, a frame, a bearing block mounted for reciprocatory movements in the frame, means yieldingly retaining the bearing block in one position of its movement a work engaging and breaking off member carried by the block, and means periodically operable to move the block from normal position to impart a work breaking-off movement to the member.
- 10 23. In a machine of the class described, a frame, a guide block mounted for reciprocatory movements in the frame, a shaft journaled in the guide block with its axis at right angles to the plane of movement of the block, a work engaging wheel carried by the shaft, means normally retaining the block in one position of its movement, means operable to periodically move the block from such position to impart a work breaking-off
- 15 25 movement to the wheel and means for driving the shaft in any position of its movement.
- 20 24. In a machine of the class described, a frame, a pair of guide blocks carried by the frame, means carried by the frame for reciprocatory movements therein, two shafts carried by the means with their axes at right angles to the movement of the means, opposed wheels carried by the shafts and between which an elongated work piece feeds, and means operable to periodically reciprocate the first means to impart a work breaking-off movement to the wheels.
- 25 25. In a machine of the class described, a frame, a pair of bearing blocks mounted for reciprocatory movements on the frame, adjustable means for connecting and spacing the blocks, means normally acting on the blocks to retain them in one position of their movement, a pair of opposed work engaging wheels carried by the blocks and movable therewith to impart a breaking-off movement to an engaged work piece, a continuously operating cam, and adjustable means connecting the cam and blocks and operable by the cam to impart predetermined movements to the blocks from normal position.
- 30 26. In a machine of the class described, means for scoring a continuously feeding work piece at predetermined intervals, and means operable to engage the work piece in advance of the scoring means and exert a combined pulling and breaking-off stress thereon.
- 35 27. In a machine of the class described, means for scoring a continuously feeding work piece at predetermined intervals, and means operable to engage the work piece in advance of the scoring means and simultaneously exert longitudinal pulling and lateral breaking off stresses thereto.
- 40 28. In a machine of the class described, means for scoring a continuously feeding work piece at predetermined intervals, and mechanism including a pair of opposed wheels operable to grip the work therebetween at a point in advance of the scoring means and to periodically impart longitudinal and lateral breaking off stresses to the work.
- 45 29. In a machine of the class described, means for scoring a continuously feeding work piece at predetermined intervals, and mechanism including a pair of opposed work gripping wheels operable to engage the work therebetween at a point in advance of the scoring means and periodically movable laterally of the feeding movement of the work to apply a breaking-off stress thereto, the wheels being driven at a speed which is greater than the speed of movement of the work.
- 50 30. In a machine of the class described, means for scoring a continuously feeding work piece at predetermined intervals, and mechanism operable to periodically engage the work in advance of the scoring means and then movable to apply a lateral breaking off stress to the work, said mechanism also being operable when in engagement with the work to apply a longitudinal pulling stress thereto.
- 55 31. In a machine of the class described, means for scoring a continuously feeding work piece at predetermined intervals, and mechanism having a pair of opposed work gripping wheels for engaging the work in advance of the scoring means and normally standing released from the work, said mechanism being operable to drive the wheels at a speed greater than the speed of movement of the work and to periodically move the wheels into gripping engagement with the work and to effect a lateral breaking-off deflection of the work.

In testimony whereof I have hereunto signed my name to this specification.

EDWARD DANNER.
